THOMAS E. CLARK, OF DETROIT, MICHIGAN.

TRACK APPARATUS FOR INDICATING THE MOVEMENTS OF RAILWAY-TRAINS.

1,242,144.

Specification of Letters Patent.

Patented Oct. 9, 1917.

Application filed February 24, 1914. Serial No. 820,709.

To all whom it may concern:

Be it known that I, THOMAS E. CLARK, a citizen of the United States, and a resident of Detroit, in the county of Wayne and 5 State of Michigan, have invented a new and Improved Track Apparatus for Indicating the Movements of Railway-Trains, of which the following is a specification.

This invention relates to automatic apparatus 10 designed for controlling the operation of railway trains, and consists of means for announcing to the engineer of one train that the second block of track in advance is occupied by another train, and for stopping the 15 first train when it enters the block next to the occupied block.

This invention consists, in combination 20 with a railway track divided into blocks and a wayside circuit for each block, of a generator of high-frequency, high-potential current for each block, of a variable connection between the generator and the wayside circuit of each block so that the frequency and wave length of the current passing to 25 the wayside circuit of any block may be varied when a predetermined block in advance is occupied.

It further consists of connections between 30 the current generators of adjacent blocks whereby, when one of the blocks is occupied, the transmission of current in one of the next adjacent blocks is interrupted and the frequency and wave length of the oscillations in the second block in the same direction are modified so long as the said block is occupied.

It further consists in the installation of 40 translating devices and electric circuits on a locomotive or other moving vehicle whereby certain instrumentalities to signal to the engineer the presence of a vehicle in the second succeeding block ahead of the track and other instrumentalities to cause the stopping of the locomotive when the next block ahead 45 is occupied may be controlled.

It further consists in the installation of an automatic controlling device which will prevent the locomotive exceeding a predetermined speed when the second block ahead 50 is occupied, and from exceeding another predetermined speed when the next block ahead is occupied.

In the accompanying drawings Figures 1 and 2 constitute a diagrammatic disclosure 55 of this present invention when joined at the lines A—A, and the same reference charac-

ters refer to like parts throughout both figures.

It has been suggested that locomotives may be controlled by electrically energized 60 means to hold closed certain train-valves of the air brake systems during such time as the next block of the track, in advance, is unoccupied. The current to the valve controlling device is to be dependent upon a 65 proper relay, which is to be energized by current impressed upon a receiving circuit on the vehicle from a way-side circuit. So long as the block in advance is unoccupied, the train-valve is to remain closed, but if 70 the locomotive enters a block next to one that is occupied, the apparatus is to immediately cause the brakes to be set. If the train thus entering is running at high speed, the sudden application of the brakes may 75 cause great damage.

It is therefore desirable to cause the approaching train to check down to a predetermined speed during the time that it is passing over the track next adjacent the entrance of the block in which the brakes will be automatically applied, so that, at the time the brakes are applied, the effect will be 80 unobjectionable.

Means are therefore provided for checking down the approaching train, for signaling the engineer, and for stopping the train. In the following description, the blocks will be termed the "clear" block, the "caution" block, the "danger" block and 85 the "occupied" block. It will be understood that the mechanism of all the blocks are similar and that each block becomes in turn "occupied," "danger," "caution" and "clear" as the trains proceed. 90

In the drawings, five blocks and four transmission installations are shown, termed respectively blocks A, B, C, D and E, in the direction of movement of the trains and an alternating current is supplied to the controlling and generating devices of each block by means of wires 1 and 2, leading from any current source. The rails 3 and 4, are divided into blocks by means of proper insulation 5. These rails are connected to the 100 wires 1 and 2 by means of track circuits consisting of wires 6 and 7 leading to the switch 8, the transformer 9-10, the wires 13 and 14, the armatures 15 and 16 of the relay 17 and the wires 18 and 19. From the 105 rails 3 and 4 the wires 21 and 22 connect to the primary winding 23 of the three posi-

tion relay 24, having armatures 25 and 26. So long as the block in advance is "clear," the armatures 25 and 26 will be swung in one direction, say to the left, as indicated at the right of Fig. 1, if the block in advance is "occupied," the armatures will be at neutral position, as indicated at the left of Figs. 1 and 2, and when the block in advance is "danger," the armatures will be swung in the opposite direction, as indicated at the right of Fig. 2.

The drawings show four generator stations, for high potential, high frequency current, one for each of the blocks A, B, C, and D, and these are indicated by A G, B G, C G and D G, respectively. Each generator is controlled by the track circuits of the two blocks next in advance. When the block next in advance is occupied the current is cut off, but if the second block in advance is occupied, caution signals are sent out.

When the block in advance is "clear," the parts will be in position shown at D G. Current will pass from wire 1 over wire 30, switch 31, wires 32 and 33, armature 34, and wire 35 to the reactance 36, over wire 37 to the primary of the transformer 38, over wire 39 to the armature 40 of the relay 42, and wires 43 and 44 to the switch 31, 30 and over wire 45 to the line wire 2. The wire 39 could connect directly to the wire 44, but experience has shown that for the operation of the relay 42 and armature 34, a companion armature 40 is desirable, and therefore the wire 39 is connected to the armature 40.

Between the rails of each block is the main limb 46 of the wayside circuit, extending substantially the length of the block, 40 its front end terminating a short distance back from the end of the block and its rear end extending the same distance into the block in the rear. A pick-up or counterbalancing limb 47 extends along the outer 45 side of the front end of the track from the end of each block back some distance beyond the front end of the main limb. The length of the counterbalance being preferably at least one hundred feet, and the distance between the end of the main limb and the end of the block being greater than the length of a locomotive.

The transformer 38 may include a spark gap 50 and condensers 51 of any desirable 55 type, as well as a tuning coil 52. A wire 53 connects one end of the coil 52 to the transformer and another wire 54 connects this end to the counterbalancing limb 47. A condenser 51 constitutes an adjustable 60 capacity which assists in balancing the capacity of the limb 47 of the wayside circuit. A wire 55 connects the other end of the coil 52 to the main limb 46. The wire 60 connects the transformer to the armature

59 of the relay 58, and wires 56 and 57 may 65 connect this armature to the coil 52, the connection by wire 56 resulting in a change in frequency of the current in the wayside circuit, preferably less than when by wire 57. When the wayside circuit receives its current over wire 57, the signals in the vehicle indicate "clear" while the current over wire 56 results in "caution" signals. It will therefore be seen that if the relay 58 is energized, "caution" current indications occur 75 in the wayside circuit.

As stated before, a track circuit consisting of the wires 18 and 19 conveys current to the rails, and normally this circuit passes over the wires 21 and 22 to one of the windings 23 of the three position relay 24. But if this circuit is bridged, as by the wheels and axle 80 of a locomotive, no current will pass to the winding 23, and the armatures 25 and 26 will be at "neutral". See C G. 85 A fifth relay 62 has armatures 63 and 64, the former adapted to close the circuit between the wire 32 and the wire 65 connecting to the relay 58, and the latter adapted to close the circuit between this wire 32 and the wire 66 leading to the inductance. This relay 62 also determines whether the signals shall be "clear" or "caution".

Connecting to the transformer 9-11 are wires 70 and 71. The former connects to 95 the wire 72 of the secondary winding of the relay 24 and then by wire 73 to the wire 71. It also connects to the armatures 25 and 26. When the block in advance is clear, and the main winding 23 of the relay 100 24 receives a positive current, causing the armatures 25 and 26 to swing to the left, current will pass from the armature 26 to the wire 74, to the relay 17 and to the wire 71, causing the armatures 15 and 16 to assume the positions shown in D G.

But if the track is not clear, the conditions indicated in station C G are present. The axle and wheels 80 short circuit the rails 3 and 4 and the current over the wires 21-22 110 will be insufficient to energize the relay 24 and move the armatures 25 and 26 from neutral position. Hence no current will pass over the wire 76 to the relay 42 or over the wire 77 to the relay 62. The relay 62 when 115 energized closes the circuit between the wire 32 and the reactance 36 by means of the armature 64, while the relay 42 when energized closes this circuit by means of the armature 34. When neither is energized 120 there will be no circuit to the transformer 38. Furthermore, when the armatures 25 and 26 are as in D G, under "clear" conditions and the relay 42 is energized, the variable reactance 36 is short and strong current 125 flows to the transformer. At the same time the secondary or high potential circuit consisting of the wire 60, armature 59, wire 57,

coil 52 and wire 53 is short, insuring high frequency current passing to the wayside circuit. But when the armatures 25 and 26 are to the right, as at B G, under "caution" conditions, and the relay 62 is energized, the operable reactance 36 is greater, and the current flow to the transformer is weaker. At the same time the armature 63 closes the circuit between the wire 32 and the wire 65 to the relay 58, which swings the armature 59 up to close the circuit to the tuning coil 52, over the wire 56, thus reducing the frequency of the high-potential current.

15 We have then a high-frequency strong current when the armatures 25 and 26 are as shown at D G, and a lower-frequency current of less strength when these armatures are as at B G. The former current will be 20 termed the "clear" current, the latter the "caution" current. When these armatures are as at C G, there is no current in the wayside circuit and the conditions are termed "danger". These armatures are controlled by the double windings of the relay 25. The current of the secondary winding of this relay is over the wires 70-72 from the transformer 9-11 and over the wires 73-71 back again, or the reverse, and is 30 constant. The primary winding 23 of this relay connects to the rails 3 and 4 by the wires 21-22 and the track connects to the armatures 15 and 16 by the wires 18 and 19. Now, whether the current flows in one direction or the other over this winding 23, will 35 depend upon the positions of the armatures 15 and 16, and they in turn are positioned according to the relay 17, and this in turn depends upon the relay 24.

40 Referring now to C G, the armatures 25 and 26 being at neutral, the circuit to wire 74 is broken and the relay 17 is not energized. The armature 15 connects to the wire 18 and armature 16 to the wire 19. 45 This causes a flow of current which may be said to be to the rail 4 over wire 22 to winding 23 of B G, and then over wire 21 back to C G, resulting in swinging the armatures 25 and 26 of B G to the right, the closing 50 of the circuit to the relay 62 and in "caution" signals. If the generator were transmitting "clear" current, or "caution" current, the armatures 25 and 26 would close the circuit to the wire 74 and relay 17, 55 swinging the armatures up to the position of D G, and causing the current to flow in the opposite direction in the winding 23 and the armatures 25 and 26 to be as in D G. The armatures of all the stations will be as 60 D G, excepting when a block is occupied when the next station in the rear will be as C G, and the second in the rear will be as B G. The locomotive 80 will receive "clear" current, the locomotive 81 will receive "cau-

tion" current, while a locomotive in block 65 C will receive no current whatever.

On each locomotive may be mounted certain translating devices of any desired description, proper signaling and other safety devices, a proper source of current to actuate the safety devices, and circuits between them, as well as receiving circuits upon which the high-potential high-frequency current from the wayside circuits may be impressed. The installation in Fig. 1 is in 75 the condition when receiving "clear" current from the main receiving circuit, that in Fig. 2 when receiving "caution" current.

Mounted on the locomotive or other vehicle whose speed is to be controlled is any 80 proper current receiving device 82, positioned about from eight to twelve inches above the main wayside circuit limb 46, and two other harps 83, similarly positioned with respect to the pick-up limb 47. Wires 85 84 and 85 lead from these receiving harps to the controlling devices on the vehicle. The wire 84 connects to the "clear" inductance 86 and the "caution" inductance 87, while the wire 85 connects to the "pick-up" 90 inductance 88, condensers 89 being installed if desired. As "clear" conditions normally exist, the circuits therefor will first be followed.

A wire 90 connects to the inductance 86 95 and to the armature 91 of the main relay 92, and a wire 93 connects to the translating-relay 94, which connects to a tuning coil 95. A wire 96 comes from this coil to the ground, preferably, to the axle 80. The 100 current passing through this relay causes its armature 97 to close the local circuit from the bus-bar 98, over the wire 99 to the relay 92, then over wire 100, armature 97 and wires 101, 103 to the bus-bar 102. 105 Wires 104 and 105 and switch 106 connect these bus-bars to the current source, preferably a storage battery 107. So long, therefore, as current passes to the main relay 92 and the translating-relay 94, the parts 110 will remain in the position shown in the upper part of Fig. 1, but to attain these conditions, other means including the "pick-up" are necessary, the functions of which 115 are as follows:

When a train has been stopped in a block where no current flows in the wayside circuit, the engineer can close a switch as hereinafter explained, and the locomotive can then proceed slowly until the end of the 120 block is reached, at which point the locomotive may wait. The pick-up harps receive current from the counterpoise 47 of that block. If the block ahead is unoccupied, current will pass over the wire 85, inductance 88, wire 110, armature 91 (which has fallen when relay 92 becomes deenergized because of the opening of the circuit 125

- by the falling of armature 97) wire 93 to the translating-relay 94, causing the armature 97 to close the circuit to the relay 92 and the armature 91 to break the pick-up 5 circuit and to close the main receiving circuit. It will be noticed that the limb 47 of the wayside circuit of block B, overlaps the main line 46 of block C. If the block E is unoccupied, block D may be "caution," 10 but block C will be "clear," and so if a locomotive is over the limb 47 of block B and the end of the limb 46 of block C, and the current over the wire 85 has caused the relay 92 to be energized, the main receiving 15 circuit will be closed. If the block C is not "clear," the armatures 97 and 91 will merely vibrate and the signals will indicate the existing conditions, as hereinafter set forth.
- 20 A valve 114 for the pipe 115 to the whistle 116 is kept closed by a solenoid 117, while the valve 118 of the air-brake system is kept closed by the solenoid 119. The circuit to the whistle valve is from the bus-bar 98 over the wire 121, armature 122, of the main relay 92, wire 123 to the solenoid 117 and then by wire 124 to the bus-bar 102. The circuit to the train valve is from the bus-bar 98 over the wire 125 to the armature 126 of the main relay 92, wires 127 and 128 to the solenoid 119, and wires 129 and 130 to the bus-bar 102. A green lamp 131 receives current over the wire 132 from the wire 123 and connects to the bus-bar 102 over wire 133. Each time the main relay 92 is deenergized, the armature 122 will fall and the lamp will be extinguished. Thus when pick-up receives a current while the main receiving circuit receives "caution" 35 current or none at all, the lamp 131 will "wink."
- 40 Mounted on the locomotive or in one of the coaches is a visual signal 135 having a hand 136 that will be held vertical when a current passes in over the wire 127-137 to the signal, will be inclined, as in Fig. 2, when current passes in over the wire 138, and will be horizontal when no current passes. This signal is well known in block-45 signal systems and need not further be described. The current passes to the bus-bar 102 over the wire 139.
- 45 When no current flows through main relay 92, the armature 126 will close the circuit 55 to the alarm lamp 141, consisting of the wire 125, armature 126, wire 142 to the lamp and wire 133 to the bus-bar 102. This lamp will therefore burn for both "danger" and "caution."
- 60 When "caution" current is impressed upon the main receiving circuit, it will pass the inductance 87, then over the wire 144 to the armature 145, as shown in Fig. 2, thence over the wire 146 to the secondary translating-relay 147 and tuning coil 148 to the 65 wire 96 and to the ground. This energizing of the relay 147 causes the closing of the circuit consisting of the wire 149, armature 150, wire 151, secondary relay 152 and wire 153 to the bus-bar 102, causing the relay 70 75 152 to be energized. This causes the armature 155 to close the circuit from the bus-bar 98, over wires 149 and 156, armature 155 and wires 157, 127 and 128 to the solenoid 119 of the train valve, which is held closed 80 while "caution" current is impressed on the receiving circuit. When neither relay 92 or 152 is energized, the solenoid 119 receives no current and the train valve opens, stopping the train.
- 85 Current also passes from the bus-bar 98 over the wires 149, 156 and 159 to the armature 160, and by wire to the signal 135 so that "caution" shall be indicated. No current passes to the solenoid 117 of the whistle 95 116, which therefore sounds continuously.
- 90 Mounted on the locomotive is a magnetically controlled valve 162 of the air-brake system of any desired construction, adapted to be opened when a proper current passes 95 through its solenoid coils. A dynamo 163 is mounted so that it may be driven in proportion to the speed of the train, a friction wheel 164 on its shaft 165 in contact with a wheel 166 on the axle 167 being shown. A 95 100 wire 168 connects this dynamo to the valve 162, while an armature 169 closes the circuit between the opposite poles of the dynamos and valves by means of the wires 171 and 172. Thus, when the "caution" relay 152 is 100 energized, the valve 162 will be opened when the dynamo 163 and the locomotive exceed a certain speed.
- 105 From the above, it will be noticed that the locomotive may pass from a "clear" block 105 into a "caution" block, but that when this occurs, the valve 162 will be opened until the movement of the train is reduced to a predetermined speed, say twenty miles per hour. The brakes can be gradually applied 110 and the speed gradually reduced until the permissible speed is reached. But when the locomotive passes from a "caution" to a "danger" block, the valve 118 opens and the train is stopped. At this time it may be desirable for the stopped train to proceed slowly in order to ascertain the cause for the "danger" signals, for it may happen that the signals were caused by a wire or metal rod lying across the rails.
- 115 To release the brakes and close the valve 119, the following described mechanism may be employed. Two relays 175 and 176 are provided with proper armatures 177 and 178. A control switch 179 may be mounted at any 125 convenient place in the cab of the locomotive, and a second switch 180 may be in circuit with the first and mounted at any desired location. When these switches are closed a current will pass from the bar 98 130

over the wire 125, armature 126, wires 142, 182 and 183 to the relay 176 and then over wires 184 and 185 to the switch or switches and wires 186 and 133 to the bar 102. When the relay 176 is energized the armature 178 causes the contacts on the ends of the wires 187 and 188 to engage. As a result a new circuit from the bar 98 over wire 125, armature 126, wire 142, 182 and 183 to the relay 176, over wires 187 and 188 to the bar 102 is formed, resulting in the relay 176 remaining energized until the main relay 92 is again energized because of high frequency "clear" current being impressed on the pickup coil 88, which results in the armature 126 opening the circuit.

The energization of the relay 176 and the closing of the circuit between the wires 189 and 190 results in the following circuit: From the bar 98, the current follows the wires 190, 189, 127 and 128 to the solenoid 119, thence over wire 124 to the bar 102. So that, if the main relay 92 is deenergized, the momentary closing of the switches will cause the closing of the valve 118.

When the control switches are closed and the locomotive is moving along in a "danger" block, it is very desirable that it shall not exceed a predetermined low speed. The relay 175 is connected to the dynamo 163 by wires 193 and 194, so that when the current generated by the dynamo becomes sufficiently strong, the armature 177 will be swung to separate the ends of the wires 182 and 183 and of wires 184 and 185. This will open the circuit to the other relay 176 and permit the separation of the wires 189 and 190, and thus the opening of the circuit to the train valve solenoid 119. The slow moving stick-relay will keep the circuits to the solenoid 119 open for a time after the speed of the train has fallen below a predetermined rate.

It will therefore be seen that this mechanism will begin to slow down a fast passenger train as it enters the "caution" block and will stop it as it enters the "danger" block, while a slow moving train may move through the "caution" block, at its usual speed, only to be stopped in the "danger" block. To suddenly stop fast trains may seriously injure the passengers and the cars, so that it is desirable to slow down such trains before they reach the "danger" block, while to check a slow moving train before it enters the "danger" block would be to waste time. If the train ahead keeps moving, the train following may continue to follow from block to block under "safety" or "caution" conditions.

The details of construction form no part of this invention, as all the parts indicated may be of any desired construction and may be modified to meet the various conditions under which they are to be used.

I claim:

1. In an apparatus for indicating the movements of railway trains, the combination of a railway track divided into blocks, a circuit connecting a source of current to each block, a relay controlling each circuit, a wayside circuit for each block, a generator of high-frequency high-potential current for each wayside circuit, each generator including an oscillating circuit, a second relay to control each said oscillating circuit whereby the frequency and wave length of the current passing to its wayside circuit may be varied, a third relay to control the first and second, and a circuit between the rails of the block in advance and the third relay. 70

2. In an apparatus for indicating the movements of railway trains, the combination of a railway track divided into blocks, a circuit for each block connecting the rails thereof to a source of current, a relay controlling each said circuit, a wayside circuit for each block, a generator of high-frequency high-potential current for each wayside circuit, a second relay to control each said generator and vary the wave length and frequency of the current passing to the wayside circuit, a third relay to control said second relay, and a circuit between the rails of the block in advance and the third relay. 85

3. In an apparatus for indicating the movements of railway trains, the combination of a railway track divided into blocks, a circuit for each block connecting the rails thereof to a source of current, a relay to change the current passing over each said circuit, a wayside circuit for each block, a generator of oscillating current for each wayside circuit, a second relay to control the first relay and to control the generator of each block, and a circuit between the rails of the block in advance and said second relay. 95

4. In an apparatus for indicating the movements of railway trains, the combination of a railway track divided into blocks, a wayside circuit for one of the blocks, a generator of oscillating current for said wayside circuit, a relay to control said generator and the wave length and frequency of the current passing to the wayside circuit, a second relay to control the first, a circuit between said second relay and the rails of the block ahead, a circuit between said rails of the block ahead and a current source, a third relay controlling said circuit to vary the current passing to said block, a circuit connecting, a fourth relay to control the third, a circuit between the rails of the second block in advance and said fourth relay, and a circuit between said rails of the second block ahead and a current source. 110

5. In an apparatus for indicating the movements of railway trains, the combination of a railway track divided into blocks, 130

- 5 a wayside circuit for one of the blocks, a generator of oscillating current for said wayside circuit, electro-magnetic means to control said generator and the wave length and frequency of the current passing to the wayside circuit, a circuit between said electro-magnetic means and the rails of the block ahead, a circuit between said rails of the block ahead and a current source, a relay 70 controlling said circuit for controlling the direction of the current passing to said rails, electro-magnetic means controlling the position of the relay, a circuit between said last named electro-magnetic means and the 75 rails of the second block ahead, and a circuit between the rails of the second block ahead and a current source.
- 10 6. In an apparatus for indicating the movement of railway trains, the combination of a railway track divided into blocks, a wayside circuit for each block, a generator of high-frequency high-potential current for each wayside circuit, electro-magnetic controllers adjacent the generator whereby 20 the frequency and wave lengths of the current oscillations in the wayside circuits may be varied, and electric circuits between said controllers and the rails of the second blocks in advance whereby the actions of the controllers are governed.
- 15 7. In an apparatus for indicating the movement of railway trains, the combination of a railway track divided into blocks, a wayside circuit for each block, a generator of high-frequency high-potential current for each wayside circuit, electro-magnetic controllers adjacent the generators whereby the frequency and wave lengths of the current oscillations in the wayside circuits may 25 be varied, and electric circuits between the controllers and the rails of the blocks whereby the action of the controllers are governed.
- 20 8. In an apparatus for indicating the movements of railway trains, the combination of a railway track divided into blocks, a current source for each block and a connection between said source and the rails of the block, a relay controlling said connection 30 to determine the direction of current passing to its block, a wayside circuit for each block, a generator of oscillating current for each wayside circuit, an electro-magnetic device for each block in operative relation with 35 its generator and with its relay in the track circuit for controlling said generator and relay, and a circuit between each said electro-magnetic device and the rails of the block in advance.
- 35 9. In an apparatus for indicating the movements of railway trains, the combination of a railway track divided into blocks, a current source for each block and a connection between said source and the rails of the block, a relay controlling said connection 40 to determine the direction of current passing to its block, a wayside circuit for each block, a generator of oscillating current for each wayside circuit, an electro-magnetic device for each block in operative relation with its generator and with its relay in the track circuit for controlling said generator and relay, and a circuit between each said electro-magnetic device and the rails of the block in advance.
- 45 10. In an apparatus for indicating the movements of railway trains, the combination of a railway track divided into blocks, a current source for each block and a connection between the rails of each block and said current source, a relay controlling said connection to determine and vary the current passing to said rails, a wayside circuit for each block, a generator of oscillating current for each wayside circuit, a three-position relay for each block in operative relation with its generator for controlling the wave length and frequency of oscillations of the current passing to the wayside circuit and in operative relation with said first named relay to control the character of the current passing to the rails, and a circuit between each said three-position relay and the rails of the block ahead.
- 50 11. In an apparatus for indicating the movements of railway trains, the combination of a railway track divided into blocks, a current source for each block and a connection between the rails of each block and said current source, a relay controlling said connection to determine and vary the current passing to said rails, a wayside circuit for each block, a generator of oscillating current for each wayside circuit, a three-position relay for each block in operative relation with its generator for controlling the wave length and frequency of oscillations of the current passing to the wayside circuit and in operative relation with said first named relay to control the character of the current passing to the rails, a circuit between each said three-position relay and the rails of the block ahead, and an additional circuit between said three-position relay and a current source.
- 55 12. In an apparatus for indicating the movements of railway trains, the combination of a railway track divided into blocks, a current source for each block and a connection between the rails of each block and said current source, a relay controlling said connection to determine and vary the current passing to said rails, a wayside circuit for each block, a generator of oscillating current for each wayside circuit, and means in each block for determining the wave length and frequency of oscillations of the current passing to the wayside circuit and in operative relation with said first named relay to control the character of the current passing to the rails, a circuit between each said three-position relay and the rails of the block ahead, and an additional circuit between said three-position relay and a current source.

relation with said first named relay to control the character of the current passing to the rails, said means being controlled by the current in the rails of the block in advance.

- 5 13. In a train control apparatus, the combination of a track divided into insulated blocks, a source of alternating electro-motive force, a tuning device for each source, a wayside circuit near the ground parallel 10 to the rails of a block comprising one limb extending from one point on said tuning device and a second limb out of alignment with the first and connected to another point

on the tuning device, a variable connection between the source and the tuning device, 15 an electro-magnet for moving said connection, and electric circuits controlled by the rails of the next two-blocks in advance for determining the action of the electro-magnet.

In testimony whereof I have signed this 20 specification in the presence of two subscribing witnesses.

THOMAS E. CLARK.
